UNITED STATES PATENT OFFICE.

PETER A. NELSON, OF WYANET, ILLINOIS.

HOISTING-BRACKET.

No. 854,302.

Specification of Letters Patent.

Patented May 21, 1907.

Application filed March 11, 1907. Serial No. 361,823.

To all whom it may concern:

Be it known that I, PETER A. NELSON, a citizen of the United States, residing at Wy-
5 anet, in the county of Bureau, State of Illi-
nois, have invented certain new and useful
Improvements in Hoisting - Brackets, of
which the following is a specification, refer-
ence being had therein to the accompanying
drawing.

10 This invention relates to a hoisting bracket,
and particularly to a structure adapted for
application to an inclined shingled roof.

The invention has for an object to provide
a supporting arm adapted at one end to be
15 inserted beneath the shingles and to receive
at its opposite end a hoisting block, together
with supporting legs extended diagonally
therefrom intermediate of its ends and a
brace for retaining said legs in proper posi-
20 tion, all of said parts being adapted to fold
into a compact position for transportation or
storage.

Other and further objects and advantages
of the invention will be hereinafter set forth
25 and the novel features thereof defined by the
appended claims.

In the drawings:—Figure 1 is a perspective
of the invention in position for use, and
Fig. 2 is a similar view of the same folded.

30 Like numerals refer to like parts in the sev-
eral views of the drawing.

Referring to the drawing, the numeral 1
designates a supporting arm which is prefer-
ably formed of a flat bar of material having
35 one angularly disposed end 2 twisted at a
right angle to the body of the bar, as shown
at 3, and suitably beveled or sharpened, as
shown at 4 for convenient insertion beneath
the roof shingles, as shown in Fig. 1. The
40 opposite end of this bar is provided with any
desired connecting device for the hoisting ap-
paratus, for instance, a hook 5 adapted to re-
ceive the block and tackle 6. Intermediate
of the ends of the bar are the supporting legs 7
45 each of which is pivoted to the bar by the up-
per portions 8 thereof which lie parallel to
each other, while the lower ends of these legs
extend diagonally in opposite directions from
the arm 1. The portions 8 are connected to
50 the bar by means of a pivot 9, and the lower
ends of the legs are sharpened as at 10 for in-
sertion into the shingles of the roof. These
legs may be formed of any desired configura-
tion, but preferably of a plate of metal folded
55 upon itself, as shown in Fig. 2, the ends there-
of being compressed together whereby a

greater strength and rigidity is secured with a
minimum weight. The arm 1 is provided
with a series of pivoting apertures 11 by
which the position of these legs thereon may
60 be adjusted to suit the pitch or inclination of
the roof and the position of the bracket
thereon.

The legs 7 are connected at their lower
ends with the arm 1 by means of diagonally
65 disposed braces 12 pivotally connected to the
legs at 13 and to the parallel links 14 at the
points 15. The braces are provided with
stop lugs 16 to retain the same in proper open
position. The inner ends of the parallel
70 links 14 are connected to the arm 1 by the
pivot 17 which may be adjusted to any de-
sired extent by means of the apertures 18 in
said arm. Under some conditions of use it
is desirable to brace the bracket against lat-
75 eral strain, and this may be accomplished by
means of the rod 19 pivotally connected to
the pivot 9 by means of the eye 20 and pro-
vided at its free end with an inserting hook
21 for insertion in the roof shingles. 8c

The operation of the invention will be clear
from the foregoing description, and it will be
seen that the same is adapted for very con-
venient application and use and can be
85 stored in a minimum space by simply folding
the parts into the position shown in Fig. 2.
When applied a rigidly supported hoisting
arm is provided which can be adjusted to any
desired position upon a barn or other struc-
90 ture, and changed in position as found desir-
able to facilitate the hoisting and storage of
material. The disposition of the diagonally
disposed legs intermediate of the ends of the
supporting arm properly braces the same
95 against lateral displacement, and provides
the extension for the application of the block
and tackle, while the adjustable connection
of these legs and their bracing connection to
the arm permits the proper adjustment for
100 differences in the pitch of the roof, and the
angle at which said arm is to be disposed.

Having now described my invention and
set forth its merits, what I claim and desire
to secure by Letters Patent is:—

1. In a hoisting bracket, a supporting arm
105 provided at one end with an angularly dis-
posed attaching portion, opposite diagonally
disposed legs pivoted to said arm intermediate
of its ends, and a brace extending from
the lower portion of said legs to said arm.

2. In a hoisting bracket, a supporting arm
110 provided at one end with an angularly dis-

posed attaching portion, opposite diagonally disposed legs pivoted to said arm intermediate of its ends, a brace extending from the lower portion of said legs to said arm, and 5 means for adjustably connecting said legs and braces to said arm.

3. In a hoisting bracket, a supporting arm provided at one end with an angularly disposed attaching portion, opposite diagonally disposed legs pivoted to said arm intermediate of its ends, a brace extending from the lower portion of said legs to said arm, and a bracing rod extending from the pivot of said legs and provided with an inserting hook.

15 4. In a hoisting bracket, a supporting arm provided at its inner end with an angularly disposed attaching portion, opposite diagonally disposed legs having parallel upper ends pivotally connected to said arm, diagonally disposed braces extending from the 20

lower portion of said legs, and parallel links pivotally connected to said braces and said arm.

5. In a hoisting bracket, a supporting arm provided at its inner end with an angularly disposed attaching portion, opposite diagonally disposed legs having parallel upper 25 ends pivotally connected to said arm, diagonally disposed braces extending from the lower portion of said legs, parallel links pivotally connected to said braces and said arm, and means for adjusting the pivotal connections of said links and legs with said arm.

In testimony whereof, I affix my signature in presence of two witnesses.

PETER A. NELSON.
